United States Patent Office

Des. 196,294

Patented Sept. 17, 1963

196,294

KNOB OR THE LIKE

Colman Zola, 58 Tamarack Way, Pleasantville, N.Y.

Filed May 7, 1962, Ser. No. 70,001

Term of patent 7 years

(Cl. D10—8)

FIG. 1

FIG. 2

FIG. 1 is a front view of the knob embodying my new design; and

FIG. 2 is a sectional view taken along line 2—2 of FIG. 1.

The dominant features of my design reside in the portions shown in full lines.

I claim:

The ornamental design for a knob or the like, as shown and described.
